Primary Examiner — Amy C Wierenga*(74) Attorney, Agent, or Firm* — Wolf, Greenfield & Sacks, P.C.(57) **CLAIM**

The ornamental design for a gasket arrangement, as shown and described.

DESCRIPTION

FIG. 1 is a top, right side perspective view of a gasket arrangement;

FIG. 2 is a top plan view thereof;

FIG. 3 is a bottom plan view thereof; and,

FIG. 4 is a front view thereof, the left side view, right side view, and rear view being identical to the front view.

The long dash-short dash lines represent the bounds of the claimed design. The broken lines shown illustrate portions of the gasket arrangement that form no part of the claimed design.

1 Claim, 4 Drawing Sheets(56)
